UNITED STATES PATENT OFFICE

2,124,543

VAPORIZER

James B. Clyne, Chicago, Ill., assignor to L.
Bruce Grannis, Chicago, Ill.

Application October 17, 1936, Serial No. 106,103

9 Claims. (Cl. 219—45)

My invention belongs to that general class of devices known as vaporizers and more particularly to what may be termed a vaporizing unit for dispensing medicants, perfumes, disinfectants, deodorizers, as well as vapors which will repel or be distasteful or even fatal to moths, flies, mosquitoes or other pests or destructive insects.

The invention has among its objects the production of a simple and novel unit of the kind described that is inexpensive, compact, attractive, durable, efficient and satisfactory for use wherever found applicable.

It has as a further object the production of a unit of the kind described which is readily adaptable for use with the desired medicant, perfume or the like, which material may be in liquid or solid form or semi-solid and applied to or embodied in a suitable porous or absorbent non-combustible base or carrier. The porous base or carrier may be applied to a support in the preferred embodiment of a lamp bulb or tube in a plastic state and allowed to harden or set and form a unitary structure with the support.

The invention has particularly as an object a vaporizer which may be constructed with an ordinary electric lamp bulb upon which may be applied a coating of a porous, absorbent material which is non-combustible or fire resisting and which may be impregnated with a suitable material which will readily vaporize when heat is applied, the source of heat for the vaporizer in the unit consisting of the light filament.

The preferred embodiment of the unit lends itself to the construction of an attractive and ornamental device of any desired size and shape.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawing, wherein like reference characters indicate like or corresponding parts:

Fig. 1 is a view in elevation of a unit embodying the invention;

Fig. 2 is a sectional view through the same;

Fig. 3 is a view similar to Fig. 1 showing the full exposure of the bulb; and

Fig. 4 is an enlarged sectional view similar to a portion of Fig. 2, illustrating the mounting of the reservoir on the unit.

Referring to the drawing, 1 represents a bulb of an incandescent lamp, radio tube or the like

which is provided with a suitable base or plug 2 for connecting the same in an electric circuit, a screw-threaded base being shown, although any other type of base may be employed. The bulb constitutes a source of heat and also forms a carrier or support for a coating 4, the filament 3 within the bulb providing the heat which is transmitted through the glass to the coating 4. The coating 4 is preferably a suitable clay, alabaster, spachet or any equivalent which is preferably porous, absorbent and non-combustible and which may be applied to the lamp bulb in a plastic state and harden so that it forms a unitary part of the bulb. The coating is impregnated with a suitable material which will vaporize and which, as hereinafter more fully described, may be embodied in the coating during the manufacture of the unit in liquid or solid form or applied thereafter in a liquid, semi-liquid or paste form by the manufacturer, user or seller, as the case may be. The lamp bulb may be frosted or roughened on the exterior or provided with a coating 6 which will tend to make the plastic adhere thereto, or a suitable adhesive such as casein or glue may be embodied in the plastic so as to improve the adherence of the same to the bulb.

The absorbent and non-combustible porous coating may cover only a portion of the bulb as shown in Fig. 1 or may cover all of the exposed bulb other than the socket or connection for an outlet, as indicated in Fig. 3. Ordinarily, it is preferred to impregnate the coating with a liquid that may be vaporized and diffused by the application of heat, and this may be applied by painting the liquid on the body or coating or by dipping the unit in the liquid or, if desired, a powdered or pulverized material may be incorporated in the body initially and when the same has been diffused, the medicant, perfume or other material may be then reapplied in liquid or semi-liquid form to recharge the unit. Obviously, the thickness and extent of the coating may be made as desired and the material to be vaporized may be applied in the desired quantity and in the desired strength, the extent and rapidity of vaporization or diffusing from the unit obviously may be controlled by the porosity of the coating, the nature of the material to be vaporized and by turning on or off the necessary switch controlling the operation of the lamp or tube.

I have illustrated a simple form of reservoir adapted to provide for the replacing of the material vaporized as the same is required. As

shown, a small container 7 is mounted on the bulb with the edge or rim 8 imbedded in the coating 4, but the same is raised or slightly spaced from the lamp bulb body to provide a space 9, as indicated in Fig. 4, so that the liquid 10 may be discharged and absorbed by the coating to replace that evaporated or diffused. The interior of the reservoir 7 may be likewise coated with the absorbent, as indicated at 4'. If the bulb is reversed, the fluid will be drawn up to the coating 4 by the capillary action. The reservoir 7 is provided with an opening 11 for the recharging of the same, the opening being normally closed by a closure 12 of any suitable type. The bulb may be of the desired size and wattage and the coating may be molded or applied substantially as shown, or it may be in the form of an ornamental design, in imitation or simulating a flower, rosette or other design.

It will be readily understood that a coating of such material as alabaster, clay, spachtel or any other absorbent body adhering snugly to the glass body of the bulb, tends to hold the heat or intensify the generated heat created by the burning filament so that ordinarily a lamp of small voltage is sufficient to diffuse various bodies whether they be in liquid or powdered form in the absorbent body. The absorbent body may be impregnated or reimpregnated by the dealer or user with the desired perfume, incense, medicant or chemical, and in this connection it may be mentioned that numerous medicants which are in jellied form may be rubbed on the bulb and absorbed and then vaporized in the manner described. The bulbs, of course, may be of any desired color or shape and likewise the coating may be of any desired color, such as red, green, blue, etc., adding to the attractive appearance of the bulbs whether the same be illuminated or not. One of the desirable features of this construction of unit is that it may be utilized in various types of electrical devices such as radio tubes and lamps for floor lamps, bridge lamps, ceiling or side lamps, urns and various places having an electrical outlet where the same may be plugged in and connected to a circuit.

Having thus described my invention, it is obvious that various immaterial modifications in the same may be made without departing from the spirit of my invention; hence I do not wish to be understood as limiting myself to the exact form, construction, arrangement and combination of parts herein shown and described or uses mentioned.

What I claim as new and desire to secure by Letters Patent is:

1. A vaporizer unit of the kind described comprising an electric lamp bulb provided with a coating of absorbent heat resisting plastic material spread directly on and enclosing the major portion of the exterior thereof; said coating susceptible to impregnation with material which will vaporize and diffuse upon the application of heat.

2. A vaporizer of the kind described comprising an electric lamp bulb provided with an ab-

sorbent plastic coating applied directly on the exterior thereof and set thereon impregnated with a vaporizing material.

3. A vaporizer unit of the kind described consisting of an electric lamp bulb of impervious material enclosing a heating element and having a coating of absorbent fire-proof material applied to the exterior thereof in a plastic state and set thereon, and a fluid reservoir mounted on the bulb and communicating with the coating for supplying a suitable fluid to said coating to replenish the fluid vaporized and diffused from the coating.

4. A vaporizer unit of the kind described comprising an electric lamp bulb of impervious material having a coating of absorbent material applied while in a plastic state to the exterior thereof and set thereon and provided with a fluid reservoir mounted on the coating and retained thereby on the bulb and arranged to maintain a suitable impregnation of said coating.

5. A vaporizer unit of the kind described consisting of a chambered support having a heating element on the interior of the chamber and a porous coating of set plastic material applied directly on the exterior of said support impregnated with a material readily vaporized during the application of heat to the coating.

6. A vaporizer unit of the kind described consisting of an electric lamp bulb constructed for attachment to an electrical outlet, said bulb provided with a coating of plastic material applied thereto and set thereon and constituting a permanent coat on the bulb of a porous nature, whereby the same when impregnated with a vaporizable material will carry the same and diffuse a vapor on the application of heat to the bulb.

7. A tubular support, a heating element arranged on the interior of said support, and plastic material applied directly to the exterior of said support and hardened thereon to provide an impregnable porous coating susceptible to absorb and retain a readily vaporizable material and vaporize the same upon the application of heat to the coating.

8. A vaporizer of the kind described consisting of a non-porous chambered support having a heating element on the interior and a coating of porous non-combustible plastic material that will readily absorb a medicant applied to and set on the exterior of the support, said porous material impregnated with a medicant material susceptible to vaporization upon the application of heat to the support.

9. A vaporizer unit of the kind described comprising an electric lamp bulb provided with a coating of absorbent heat resisting material applied in a plastic state directly on the exterior thereof and adhering thereto susceptible to impregnation with material which will vaporize and diffuse upon the application of heat, and a refillable liquid reservoir mounted on the bulb and communicating with the coating at the end of the bulb for supplying material for impregnating the absorbent coating.

JAMES B. CLYNE.
